METHOD OF AND APPARATUS FOR
ASSEMBLING STRANDSVictor S. Martin, Baltimore, Md., assignor to
Western Electric Company, Incorporated, New
York, N. Y., a corporation of New York

Application September 3, 1938, Serial No. 228,350

5 Claims. (Cl. 96—3)

This invention relates to a method of and apparatus for assembling strands and more particularly to a method of and apparatus for producing multi-conductor cords and the like.

In the manufacture of strand assemblies, for example, multi-conductor cords, it is desirable in some instances to form, such as by braiding, a protective covering or sheath on desired groups of individually insulated conductors. The life of such cords depends considerably upon the tightness or looseness with which the sheath is applied.

Objects of the invention are to provide an improved method of and apparatus for continuously, rapidly and efficiently producing strand assemblies.

With these and other objects in view the invention comprises a strand assembling apparatus, by means of which the method may be practised, including a fluted element to individually guide strands through the point of application of a sheath thereto, the element having radially extending ridges for guiding and spacing the strands to cause the sheath to lie loosely on the strands when the element is withdrawn.

Other objects and advantages will be apparent from the following detailed description when taken in conjunction with the accompanying drawing, wherein

Fig. 1 is a schematic front elevational view of an apparatus embodying the invention;

Fig. 2 is an enlarged sectional view taken substantially along the line 2—2 of Fig. 1 illustrating one embodiment of the invention; and

Fig. 3 is a sectional view taken along the line 3—3 of Fig. 2.

Referring now to the drawing, it will be observed that the apparatus of the present embodiment of the invention includes a braiding head 20 of any well known type consisting of the usual rotatable carriers for carrying the inner and outer sets of bobbins or cops 21 and 22, respectively, as illustrated diagrammatically in Fig. 1. The braiding head is mounted in a stationary housing 24 supported upon a suitable framework or pedestal (not shown). Attached at its lower end to the housing 24 and communicating with a central circular aperture in the base thereof is a vertical tube 30 which extends upwardly through the center of the braiding head 20 and has a cap 31 attached to the upper end thereof. A supporting bracket 33 connected to the cap 31 in any desired manner, such as by radially extending arms, is centrally apertured, at 34, to receive a threaded shank 35 of a gage or softening pin 38.

The gage 38 is flared outwardly at the base thereof, where it rests upon the supporting bracket 33. This outwardly flared portion in the present embodiment is divided into three lobes 40 by substantially V-shaped grooves 41, which grooves extend from arcuate surfaces 42 adjacent the base (Fig. 2) to the upper extremity of the gage. The grooves 41 may be broadly termed apertures for guiding the strands at spaced portions. The reduced portion or neck of the gage 10 is formed of a predetermined diameter, dependent upon the size or gage of the strands or insulated conductors being covered, to form ribs 45 spaced by the grooves 41 and having arcuate outer surfaces with equal radii. 15

In the present embodiment of the invention shown in Figs. 2 and 3 the strands 47, which are to be covered with a common braided sheath, are insulated electrical conductors fed from supplies (not shown) upwardly through the tube 30, 20 where they are fed through their individual grooves in the gage 38 to receive the braided covering. 25

When the apparatus is in operation the braiding head 20 is rotated by suitable means (not shown) to apply a braided sheath over the strands at a braiding point indicated at 50, after which the covered strands are directed upwardly, where they pass around a series of sheaves 51 and around the respective grooves in a capstan 52. 30 The capstan 52 is driven by suitable means (not shown) and serves as means for advancing the covered strands, which strands upon leaving the capstan are taken up on a reel or other suitable means (not shown). 35

Referring again to the gage 38, it will be noted that the lobes 40 extend outwardly sufficient distances to assure the guiding of the strands 47 into their respective grooves 41. The apices of the V-shaped grooves are rounded to permit free movement of the strands therethrough. Furthermore, the grooves are only of such depth as to leave a substantial solid portion in the central axis of the gage so as to hold the strands spaced apart. As result of this construction the strands being braided over the spaced strands and the gage at the braiding point 50 are held outwardly by the strands until the gage is withdrawn from the strands. As a result thereof the strands, as they slip over the end of the gage 50 during the advancement thereof, contract and the braid is somewhat loose. 45

The forming of a loosely braided sheath upon the strands lends flexibility to the finished cord, permitting the cord to be bent freely and repeat- 55

edly without causing possible injury to the strands or the insulation thereupon or endangering possible breaking of the sheath.

Furthermore, the gage in positively guiding the strands in definite, parallel and equally spaced paths through the braiding point assures the application of a straight and uniform braided covering thereon.

The embodiment of the invention herein disclosed is illustrative only and may be widely modified and departed from in many ways without departing from the spirit and scope of the invention as pointed out in and limited only by the appended claims.

15. What is claimed is:

1. In a strand assembling apparatus, means for forming a covering on a plurality of strands, and means for loosening the covering on the strands comprising a pin extending between strands at the point where the covering is being formed, said pin having grooves for receiving and retaining the strands in a predetermined spaced relationship while said covering is applied, whereby the covering is loosened when the pin is withdrawn.

2. In a strand assembling apparatus, means for advancing a plurality of strands therethrough, means for applying a covering to the strands, and a softening pin extending between the strands at the point where the covering is being applied, said pin having a plurality of radially extending ribs separating each strand

from another strand a predetermined amount at the point where the covering is being applied, whereby the covering is softened when the pin is withdrawn.

3. In a strand assembling apparatus, means 5 for advancing a plurality of strands therethrough, means for applying a covering to the strands, and a softening pin extending between the strands at the point where the covering is being applied, said pin having a plurality of 10 radially extending ribs for guiding the strands in a predetermined path during the application of said covering.

4. In a strand assembling apparatus, means 15 for advancing a plurality of strands therethrough, means for applying a covering to the strands, a softening pin having a plurality of grooves for spacing and guiding said strands during the application of said covering, and a support for said pin having an aperture in alignment with each groove in said pin to direct the strands into said grooves.

5. In a strand assembling apparatus, means for advancing a plurality of strands therethrough, means for applying a covering to the 25 strands, a softening pin having grooves for spacing and guiding said strands during the application of said covering and provided with a flared base, and a support for the flared end of said pin having apertures in alignment with each groove. 30 in said pin to direct the strands into said grooves.

VICTOR S. MARTIN.
